[57] CLAIM

The ornamental design for a surface ornamentation for a portion of a shoe sole, as shown and described.

DESCRIPTION

FIG. 1 is a bottom plan view of surface ornamentation for a portion of a shoe sole showing my new design; and, FIG. 2 is a bottom plan view of a second embodiment thereof.

The broken line showing of a shoe sole in FIGS. 1-2 is environmental only and forms no part of the claimed design.

1 Claim, 2 Drawing Sheets

FIG. 1

FIG. 2
